UNITED STATES PATENT OFFICE.

THEOPHILUS ZACHARIADIS, OF LONDON, ENGLAND.

SPINNING MILL.

Application filed November 3, 1922. Serial No. 598,891.

To all whom it may concern:

Be it known that I, THEOPHILUS ZACHARIADIS, a subject of the King of Greece, and residing at London, England, have invented a certain new and useful Spinning Mill, of which the following is a specification.

This invention relates to machines for spinning slivers, rovings and the like into thread and winding the thread so formed on to bobbins or the like. It has for its object the provision of an improved method and apparatus for the purposes set forth.

In machines of this kind, such as the mule and ring spinning frames, it is usual to feed the roving to the machine which spins it and to wind the spun thread on bobbins in two separate operations.

The present invention mainly consists in an apparatus for carrying out simultaneously and in a continuous and uniform manner the operations of spinning and winding.

The invention also consists in apparatus constructed and operating substantially in accordance with the following description.

One way of carrying the invention into effect is described with reference to the accompanying drawings, in which:—

Figure 1 is a sectional plan of the apparatus.

Fig. 2 is a transverse section on the line 2—2 of Fig. 1 in the direction in which the arrows point.

Fig. 3 is a transverse section on the line 3—3 of Fig. 1 in the direction in which the arrows point, and

Fig. 4 is an end elevation in part section of the mechanism for stopping the machine when the roving breaks.

In the figures, 1 and 2 are rectangular metallic frameworks screwed together at their shorter ends by screws 3 and enclosing between their longer sides parallel slots 4 and 5.

To the opposite ends of these frameworks, discs 6 and 7 are fitted. The disc 7 is secured symmetrically, by means of screws 8, to a short tubular axial shaft 9 and to the end of the rectangular frames 1 and 2, as shown. The tubular shaft 9 rotates in a ball bearing 10 carried on a base plate 11.

The disc 6 is secured symmetrically by means of screws 12 to a toothed wheel 13 and to the end of the rectangular frames 1 and 2. The wheel 13 is capable of rotation about a shaft 14 to which is keyed a toothed

wheel 15. The shaft 14 is coaxial with the hollow shaft 9 and is carried in ball bearings 16 and 17 fixed to the base plate 11. A ball thrust washer 17' is inserted between the toothed wheel 13 and the bearing 17 to reduce frictional losses.

A countershaft 18 mounted in ball bearings 19, 20 carries three spur wheels 21, 22, 23 of which the wheel 21 meshes with the wheel 15 attached to the shaft 14; the wheel 22 meshes with the wheel 13 attached to the disc 6, while the wheel 23 engages with a spur wheel 24 attached to a second counter-shaft 25.

The countershaft 25 is mounted in ball bearings 26 and 27 mounted on the base 11 and carries besides the wheel 24 a second wheel 28 which meshes with a spur wheel 29 mounted slidably upon a squared portion 30 of a main driving shaft 31. The latter receives its motion from the squared end 32 of the part 34. A dog-clutch 33, 34 is inserted in the main driving shaft in order to permit of starting and stopping the machine when required by disconnecting the continuously driven part 34 from the part 33, 30 and 31.

The main driving shaft 31, when the clutch 33 is in gear, drives through the wheels 29, 28 shaft 25, wheels 24 and 23, shaft 18 and wheels 21 and 15 to the shaft 14 and wheels 22 and 13 to the disc 6 and framework 1 and 2.

The wheels 21 and 22 are of different diameters and by a suitable choice of the sizes of the wheels of each of the two pairs 15, 21 and 13, 22, any desired ratio of the relative speeds of the shaft 14 and the disc 6 with its attached framework may be obtained.

Firmly attached to the end of the shaft 14 which projects through the disc 6 and the framework 1 and 2 is a bevel gear wheel 35 which meshes with a similar gear wheel 36 attached to a countershaft 37, which is carried in a U-shaped bearing 38 attached to the disc 6, see Figure 2. The middle portion of the countershaft 37 is formed as a worm which engages with a worm wheel 39 formed on or attached to a double tapered shaft 40 which is carried in bearings 41, 42, as shown in Figure 1, in the frame members 1 and 2. The bearing block 42 is removable from the frame and is locked in position by the slotted member 43 and the screw 44. The rotary motion of the shaft 40 is trans-

mitted through a series of spur wheels 45, 46, 47 mounted between the frame members 1 and 2 in bearings formed therein. Attached by a squared end to the last-mentioned spur wheel 47 is a shaft 48 which extends across the framework to a bearing 49 and on this shaft is mounted a carefully machined cylinder 50. The bearing 49 is secured similarly to 42. A bobbin 51 is carried in the forked ends 52 of a cradle 53 whose grooved sides 54 are adapted to slide along the framework 2. The cradle 53 carrying the bobbin 51 is urged towards the cylinder 50 by means of springs 55 whose ends engage with the slots 56 of the cradle 53 and which are anchored to the framework 1, 2 by means of the arms 57. One of the surfaces of the cradle 53 between the ends 54 is curved, as shown in Figure 3, with 20 symmetrically placed recurved portions 58.

The whole of the frames 1 and 2 together with their contents, cylinder 50, bobbin 51, etc., are enclosed from disc 6 to disc 7 by means of a cylindrical cover made in two parts, 59 and 60, and fastened to the discs and frame by rings 61, 62, 63 and 64 in such a manner that the part of the cover 59 attached to the rings 62 and 64 when detached from the disc 7 may be slid along the other part 60 attached to rings 61 and 63 in order to expose the mechanism and to remove the bobbin 51 when filled with thread.

Two metallic rings 65 and 66, one on each side of the disc 7, are connected together by bolts 67 and 68 which slide through the frame ends and the disc 7. Two or more springs on bolts, not shown, which slide through the disc 7 alone and connect the rings 65 and 66, serve to keep the ring 66 in contact with the disc 7 until the springs are compressed by the end of the bobbin cradle 53 being forced against the extended ends of the bolts 67 and 68 when the bobbin is filled with thread to a determined depth.

Fixed to the base plate 11 in any suitable manner is a box-shaped framework 69 which embraces the driving shaft 31 and extends beyond the periphery of the framework 1 and 2, as shown in Figures 1 and 4. A trigger 70 carrying a roller 71 slides in one end of the frame 69 and is held normally by a compression spring 72 in contact with the inner side of frame 69, as shown in Figure 1, and is of such a length that the roller 71 nearly contacts with the rotating ring 66 on the framework 1 and 2. A slot 73 cut in the trigger 70 allows a compressed spring 75 to move a sliding bolt 74 towards the driving shaft 31 when the trigger 70 is displaced against the pressure of the spring 72, e. g. when the cradle 53 moves the stops 67 and 68 and the ring 66. The end of the bolt 74 remote from the trigger carries a female screw-thread, shown in Figure 1, which meshes with a corresponding male

thread on the driving shaft 31 when the bolt 74 is released by the trigger 70 and serves to move the rotating driving shaft to the right, as shown in Figure 1, consequently declutching the shaft 31 from the driving shaft 34. At the end of the shaft 31 remote from the clutch 33, 34, a toothed wheel 76 serves to drive the mechanism, not shown, which feeds the roving to the machine. This consequently stops when the main machine 75 stops.

Screwed to the side of the box 69 is a standard 77 carrying on a pivot 78 on its upper forked extremity a rocker arm 79 (see Figure 4). A wire ring 80 is carried by one end of this rocking arm and is normally held axially in line with the centre of the hollow shaft 9 by the feeding roving, against the action of a slightly overbalancing counter-weight 81, linked to the other end of the rocking arm 79.

The counterweight is arranged to slide vertically in a guide 82 which is secured to a bolt 83 which is slotted to permit of movement across the driving shaft 31. The end of the bolt 83 remote from the driving shaft slides in the box 69 and also through a slot 84 in the trigger 70. A sloping surface 85 is formed on the bolt 83 as shown and coacts with a sloping surface 86 on the side of the slot 84 in the trigger 70.

An eccentric 87 rigid with the driving shaft 31 rotates freely within an enlarged portion of the box 69 when the weight 81 is held up by the roving passing through the wire ring 80. Should the roving fail to hold up the weight 81, e. g. if breakage of the roving should occur, the weight 81 descends by gravity to the bottom of the slide 82, is engaged by the eccentric 87 and moves together with the bolt 83, with the result that the sloping surfaces 85 and 86 cause the trigger to move until the slot 73 releases the bolt 74 which disengages the clutch 33 and 34 by means of the male and female screw-threads before described.

In normal operation the process is as follows:

The roving is fed by auxiliary machines; not shown, actuated by the shaft 31 by way of the toothed wheel 76. It then passes through the wire ring 80 of the stopping device and through the rotating hollow shaft 9. From the inner end of this shaft the roving passes over the curved edge of the cradle 53, laps the cylinder 50 and from the cylinder is wound on the bobbin 51.

As the bobbin derives its motion from the circumference of the cylinder it is obvious that the bobbin will revolve at all times at the correct speed to absorb exactly and without strain the spun thread which is delivered by the cylinder. The pressure of the bobbin against the cylinder caused

by the springs 55 pressing against the cradle 53 ensures an even laying of the spun thread upon the bobbin. As the bobbin fills, the cradle moves towards the stops 56, 68 until at a predetermined filling the stops slide through the end of the casing and move the trigger 70 until the bolt 74 is released by the slot 73 and the spinning mechanism is stopped as before described.

The stopping of the mechanism as a result of breakage of the roving has already been described.

The twist per unit length of spun thread, it is clear, may be varied by suitable dimensioning of the cylinder diameter and the ratio of the angular speed of the framework 1 and 2 about its axis to the angular speed of the cylinder 50 about its axis. This latter ratio may be varied conveniently by varying the sizes of the differential pairs of toothed wheels 21 and 15 and 22 and 13; but, of course, differential angular speed variations may be made in any of the members of the train from the shaft 14 to the cylinder 50.

The fact that the spinning and winding mechanism is enclosed, as shown, by the casing 59 and 60 renders the rotating mechanism, roving and thread immune from atmospheric influences, and reduces to a minimum frictional losses due to air resistance to rotation. This feature also allows of the introduction of dry or humidified air through the hollow shaft 9.

The apparatus may be arranged to work on a horizontal axis, or, with suitable modification of the gravity counterweight device, on a vertical axis.

Having now described my invention, what I claim as new and desire to secure by Letters Patent is:—

1. Apparatus for spinning a roving or the like into a thread of any desired degree of twist including a rectangular frame rotatably mounted at the respective ends thereof, a resiliently controlled cradle slidably mounted transversely of the frame, a bobbin rotatably mounted in the cradle, a cylinder rotatably mounted transversely of the frame and frictionally engaged with the bobbin to effect rotation of the bobbin, and means for driving said frame and cylinder.

2. Apparatus for spinning a roving or the like into a thread of any desired degree of twist including a rotatable frame, a bobbin in the frame, a cylinder rotatably mounted transversely of the frame and operably connected with the bobbin for rotating the bobbin, a telescopic cover arranged longitudinally on the frame for completely including the parts in the frame, and means for driving said frame and cylinder.

3. Apparatus for spinning a roving or the like into a thread of any desired degree

of twist including a bobbin for the reception of the spun thread, a rotatably mounted cylinder for frictionally driving the bobbin, a frame rotatably supported at both ends thereof and in which the bobbin and cylinder are mounted, the axis of rotation of the frame being at right angles to the axis of said cylinder, a common driving shaft and means for driving said cylinder and said frame from said common driving shaft.

4. Apparatus for spinning a roving or the like into a thread of any desired degree of twist including a rotatable frame, a bobbin in the frame, a cylinder rotatably mounted transversely of the frame and operably connected with the bobbin for rotating the bobbin, a common driving shaft composed of sections one of which is shiftable, means for driving said frame and cylinder from said driving shaft, and mechanism for stopping the operation of the spinning and winding apparatus actuated automatically when the spun thread on the bottom obtains a predetermined depth of winding including a spring controlled shaft shifting member, a trigger for releasably retaining said shifting member in a retracted inactive position, and means mounted at one end of the frame and disposed in proximity to the trigger and actuated when the thread attains a predetermined depth of winding for shifting the trigger to release the shaft shifting member.

5. Apparatus for spinning a roving or the like into a thread of a desired degree of twist including a rectangular frame rectangularly mounted at the respective ends thereof, a cradle slidably mounted in the frame, a bobbin rotatable mounted in the cradle, a cylinder rotatable transversely of the frame and engaging the bobbin to effect rotation thereof, resilient means mounted in the frame for exerting a tension on the cradle to maintain the bobbin in frictional engagement with the cylinder, a common driving shaft composed of sections one of which is shiftable, means for driving the frame and the cylinder from the driving shaft, a spring controlled shaft shifting member, a slidably mounted trigger normally maintaining the shaft shifting member in a retracted position, stops mounted in one end of the cylinder and actuated automatically by the cradle when the thread on the bobbin attains a predetermined depth for actuating the trigger so as to release the shaft shifting member to effect stopping of the apparatus.

6. Apparatus spinning a roving or the like into a thread of a desired degree of twist as claimed in claim 5 wherein a rocking arm is employed, a ring mounted on one end of the rocking arm and through which the feeding roving passes, a slidably counterweight on the other end of the arm, a cam on the shiftable shaft for engaging the counterweight when the latter is released upon the breaking

of the roving and a trigger actuating bolt operable by the cam and the released counter-weight, substantially as and for the purposes set forth.

5. 7. An arrangement as claimed in claim 2 wherein the telescopic cover is constructed in sections so as to permit of ready interchanging of empty for full bobbins.

8. Apparatus as claimed in claim 3 wherein means is employed for stopping the operation of the spinning and winding appa-

ratus including a spring controlled declutching member, a trigger for holding said member in an inactive position and means on the frame actuatable when the spun thread on the bottom attains a predetermined depth of winding for releasing the trigger. 15

In testimony whereof I have signed my name to this specification.

THEOPHILUS ZACHARIADIS.
